UNITED STATES PATENT OFFICE.

WALTHER BRUCK, OF BRESLAU, GERMANY.

DENTIFRICE COMPOUND.

No Drawing. Application filed June 28, 1926, Serial No. 119,201, and in Germany March 29, 1924.

This invention has reference to dentifrice compounds, and it refers in particular to compounds of the kind referred to which are adapted to remove the so-called "tartar" of the teeth, that is to say, the sediment or incrustation, chiefly containing lime salts and various decomposition products and precipitated upon the teeth from the saliva and from decomposition products of the food.

10 The tooth cleaning compounds usually employed are chiefly based upon a mechanical cleaning of the teeth, and in view thereof the majority of the tooth-pastes on the market contain as their chief constituent an abrasive or triturating agent, such as chalk the cleaning properties of which are increased by the presence of soap. These compounds employed by practitioners are insufficient or not suitable at all for the purpose of dissolving or removing the so-called "tartar" or upon repeated use to prevent the deposition of the tartar. Various attempts have been made heretofore to arrive at a prevention or dissolving of the deposits 20 of tartar which is a point of particular importance in the care of the teeth. Thus it has been suggested to employ certain salts of inorganic acids in compounding dental medicines, but the results were highly unsatisfactory.

25 Now, it has been found in the course of my experiments that the salts of the aromatic sulphonic acids particularly the hydroxylated sulphonates, thus for instance, the alkali salts thereof exhibit a very strong dissolving action for carbonate of lime and phosphate of lime, and for the so-called tartar of the teeth, and it has also been ascertained that these solvents retain an absolutely sufficient and satisfactory dissolving 35 action with regard to the substances mentioned even in the presence of soaps. This property is of very great importance for the practitioner, and, inasmuch as the sulphonic acids employed are absolutely harmless and indifferent and do not attack the enamel of the teeth, they are highly suitable for the manufacture of compounds to dissolve and

disintegrate the tartar of the teeth and they may be used in the form of mouth-washes, tooth pastes, tooth powders and the like.

The efficiency of the phenol-sulphonic-acid salts on being digested for only five minutes with CaCO_3 at the temperature of the room may be seen from the following details:—

Water will dissolve during this time in 100 cc. 3.8 millgrs. CaCO_3 .

0.9% NaCl solution dissolves during this time in 100 cc. 0.7 millgrs. CaCO_3 .

1% benzoate of soda dissolves during this time in 100 cc. 10.1 millgrs. CaCO_3 .

0.9% phenol-sulphonate of Na dissolves during this time in 100 cc. 15.5 millgrs. CaCO_3 .

Thus, while ordinary aromatic acids are equivalent to salt NaCl , the efficiency of the phenol-sulphonic-acid salt even with weak concentration is 50% stronger, and there is the further advantage, as compared with previous suggestions that the mixture does not act with neutral or faintly acid reaction, which is not practicable in dentistry, but that it is efficient at a decidedly alkaline reaction (concentration index $P_H=7.8$).

Example.

	Per cent.
Sapo medicin	23
Glycerine	25
Tinct. benzoic	2.0
Alcohol	19
Abrasive (talc or the like)	21.0
Para-phenol-sulphonate of Na	10
	100

add perfume at discretion.

The employment of aromatic sulphonic acids in such compounds is broadly novel and constitutes a very important progress in the art.

It should, of course, be understood that the invention is not restricted to the particular proportions and ingredients, herein mentioned by way of exemplification and illustration of the principles of the invention, but changes and modifications are admissible within the spirit and scope of the

invention, as particularly pointed out in the appended claims.

I claim:—

1. As a dental compound, a composition of matter, comprising a mixture of hydroxy aromatic sulpho-compounds with mechanical tooth cleaning agents.
2. As a dental compound, a composition of matter, comprising a mixture of an abrasive with hydroxy aromatic sulphonic acid salts.
3. As a dental compound, a composition of matter, comprising a mixture of an abra-

sive with alkali-salts of hydroxy aromatic sulphonic acids.

15

4. A dentifrice, comprising hydroxy aromatic sulphonic acid compounds.

5. A dentifrice, comprising alkali metal salts of phenol sulphonic acids.

6. A dentifrice, comprising a mixture of 20 soap with an abrasive and phenol sulphonic acid compounds.

7. A dentifrice, comprising a mixture of soap with an abrasive and alkali-salts of phenol sulphonic acids.

WALTHER BRUCK.
